UNITED STATES PATENT OFFICE.

WILLIAM M. HENDERSON, OF MORTON, PENNSYLVANIA.

STEAM-ENGINE.

SPECIFICATION forming part of Letters Patent No. 339,292, dated April 6, 1886.

Application filed May 20, 1885. Serial No. 166,152. (No model.)

To all whom it may concern:

Be it known that I, WILLIAM M. HENDERSON, a citizen of the United States, residing at Morton, in the county of Delaware and State 5 of Pennsylvania, have invented certain new and useful Improvements in Steam-Engines; and I do hereby declare the following to be a full, clear, and exact description of the invention, which will enable others skilled in the 10 art to which it appertains to make and use the same, reference being had to the accompanying drawings, in which like parts are marked in the same manner.

My invention relates to an improvement 15 upon that class of engines known as "multiple-cylinder engines," and the object is to economize the use of steam in their operation by means of compounding the cylinders and providing simple and durable pistons, which, 20 by the addition of a simple groove turned midway in their length, fits them to serve as the steam-valves, in connection with an improved arrangement of steam-distributing ports, together with certain other novel im- 25 provements in the form of connecting-rods and their bearings; also, in the matter of lubri- 30 cation of the working parts and protecting the cylinders from undue condensation, and a general improvement in the manner of arranging the cored ports in the cylinder-casting, 35 whereby the construction is greatly simplified, and the operation rendered more efficient and permanent than heretofore, as hereinafter more fully described.

The modern compound engine in the form 40 it has most obtained is that in which two cylinders are used—high and low pressure—and it is my aim to construct an engine of this type, using a three-throw crank as an expedient to do away with all valve-gear. In order, therefore, to have a cylinder for each 45 crank, I divide the required area of the low-pressure cylinder into two cylinders of equal size, and use the high-pressure cylinder on the first crank.

Figure 1 represents a longitudinal section 50 of my improved engine. Fig. 2 is an end view of the crank-shaft. Fig. 3 is a vertical section, drawn to an enlarged scale, of one of the trunk-pistons, showing the form of connecting-rod and the manner of making the upper bearing-joint alike for the several cyl-

inders. Fig. 4 is a cross-section showing the interior of the intermediate receiver, taken through the line X X of Fig. 5, which is a 55 horizontal section through the line of cylinders, showing the plan of the steam and exhaust ports and passages, taken on the zigzag line v v of Fig. 4, the part below the line W W being taken through the steam-ports, and 60 the part above that line being taken through the exhaust-ports. Fig. 6 is a plan of the cylinder-cover. Fig. 7 is a diagram of the valve-motion, and Fig. 8 is a plan and section of one of the fly-wheels used. Fig. 9 is a sec- 65 tion showing a mere formal modification, in which the third cylinder is twice the area of the second, the section being taken through the exhaust-ports, and the steam-ports being indicated by dotted lines.

A is an inclosed crank case or housing for the engine, containing the lubricating material required for the running parts, upon which are mounted the three working-cylinders, (marked 1 2 3 in Figs. 1, 6, and 9.)

B is a crank-shaft, the parts of the shaft 75 (marked 1, 2, and 3 in Figs. 1, 2, and 8) which form the crank-pins being in the relative position of the angles of an equilateral triangle. This shaft runs in long phosphor-bronze bearings, secured in the heads C C', which are bolted to the crank-case, as shown.

D, Fig. 3, shows the form of the connecting-rods, which are all alike. It will be observed that no cross-head pins are used. The upper 85 ends of the connecting-rods are in the form of a ball working in composition sockets, forming ball-and-socket joints. The lower part of the socket after being turned is sawed in two and made to embrace the neck of the ball. The 90 rod being passed through the neck of the piston to receive it, is then lowered in place, the top cap put in position, and the whole secured by the follower F, which also secures the spring packing-ring, as shown. At the 95 lower end of the rod half-boxes of phosphor-bronze are used for receiving the thrust, which is always in a downward direction. The lower half of the box may be of cast-iron secured by a turned bolt and nut with split pin to prevent coming apart under the strains of very rapid revolution. At the lower end of each 100 trunk-piston there is attached a cover-plate, H, slotted to form an opening only sufficient

to allow the vibration of the connecting-rod. The object of this is to prevent that splashing of the cold contents of the case into the interior of the hollow pistons which generally occurs in engines of this class, with a view to lubricate the upper pin of the rod. The vice of such plan of lubricating the pin is, that it converts the hollow pistons into a species of surface-condensers, not only wasting the working-steam by unnecessary condensation, but also unduly heating the lubricant, and thereby the journals.

The lubrication of the upper pin I accomplish in a different manner, not requiring the splashing or involving the objections stated.

I make the socket-bearings of a composition of copper and tin, and provide a recess in the follower F of the piston communicating with the interior of the cap by a small drilled hole, O, through which steam condensed on the head of the piston will enter to the bearing. This introduction of condensed steam, with the composition socket-bearings employed, renders further lubrication unnecessary.

With a view to further guard against cooling the steam-cylinders than is done by the plate H, I protect their bottoms below the steam-line with a shield of wood or other non-conducting material, M, as shown.

The phosphor-bronze bearings of the shaft-journals are simply sleeves secured in the cast-iron heads either by a key or set-screw, or in any other suitable manner. The boss on the head is swelled, leaving a circular cavity to contain cotton wick or other suitable material, to absorb and hold the lubricant from the case in constant proximity to the running shaft. The fluid enters by the hole marked z and finds its way to the oil-holes N, drilled in the upper part of the sleeve. A constant lubrication of the journals is thus maintained, and the fluid from the case having free access to the journal-boxes must keep them in a cool condition. The shaft, it will be noticed, is further supported on Babbitt-metal bearings, as shown by the supports G G', Fig. 1.

Cylinder No. 1 is the high-pressure, and cylinders Nos. 2 and 3 are the low-pressure cylinders. The latter are of the same size, the area of each being twice the area of cylinder No. 1, and their collective capacity being four to one of that cylinder. Thus it will be noticed that although three cylinders are employed the effect is very much the same as given by the popular compound engine having two cylinders—high and low pressure. The stroke of all the pistons is the same. The position of each crank-pin center is just where the center of an eccentric would be required to be to cut off the steam at three-fourths of the stroke of the piston attached to the next following crank. The movements are so timed that crank No. 3 gives steam to the piston in cylinder No. 1 when the latter arrives at the top of its stroke. Crank No. 1 performs the same function for the piston of cylinder No. 2, and crank No. 2 performs the same function for

the piston of cylinder No. 3. Taking advantage of this established property of the three-throw crank, a simple annular groove turned in the body of each piston fits it to act as a valve for the piston connected to the next following crank. The pistons are all alike for the three cylinders, except as to diameter, as before explained. It will be observed that the groove in the piston being circumferential it is not affected by side-thrust, producing friction and leakage, as would be the case where receivers are formed on a piston for the purpose of receiving and transmitting steam.

The operation is as follows: Steam from the boiler connects with the inlet marked S', and when the piston of cylinder No. 3 descends the groove therein comes into position to receive the steam and pass it across to the steam-port S P. Thence it passes by the long passage P² and enters the head of the high-pressure cylinder No. 1, meeting its piston just as it arrives at the top of its stroke and follows it down to three-fourths of the stroke, at which point the steam is cut off by the groove in the piston of cylinder No. 3, which, after reaching its lowest point, rises beyond the port S P. By the time the No. 1 piston reaches its lowest point the groove of No. 3 piston commences to establish a connection with the exhaust-port E P, and the steam from the cylinder No. 1 (which has performed its duty of carrying the high-pressure piston to the end of its stroke) returns by the same passage, P², and is discharged into the receiver R through the exhaust-port E', situated on the same plane as the port E P, so that when the circumferential groove comes opposite port E P it also coincides with the exhaust-port E', which is a simple hole east through the wall of cylinder No. 3, opening at once without obstruction into the receiver. The groove of piston No. 1 now performs the function of a valve for the piston in cylinder No. 2 and admits the steam from the receiver thereto in the same manner as just described, and the groove of piston No. 2 performs the same duty for the piston of cylinder No. 3, completing the cycle. The exhausts from the low-pressure cylinders, having thus been expanded to as low a tension as efficiency requires, are now discharged into the atmosphere or condenser. In the high-pressure cylinder the final exhaust, E², is made the same height as the other ports, and a supplemental exhaust, E', is provided, disconnected therefrom and opening into the receiver, so that when the upper edge of the high-pressure piston descends below the upper line of this supplemental exhaust the discharge is made into the receiver R. In the low-pressure cylinder No. 2 the final exhaust is made twice the height of the other ports, and when this piston reaches its lowest point the upper edge thereof descends a little below the upper line of the exhaust-port E², giving a supplementary exhaust. The remaining exhaust, E', on cylinder No. 3 is in height the same as the depth of the groove in the piston.

This feature of exhausting at the end of the stroke in a steam-engine by the piston passing beyond apertures formed in the walls of the cylinder I am aware is not new *per se*. It is 5 fully described in the English patent granted to William Henry James in 1864, No. 1,445. Lead is given to the exhaust by cutting away in whole or in part the upper edge of the annular groove of the piston-valve, as shown by 10 Y on Fig. 3. This prerelease of the steam is common, and especially advantageous in fast-running engines. There is another advantage of greater importance in cutting away this upper corner. By reference to Fig. 1 it will 15 be observed that the piston of No. 2, moving in the direction of the arrow, has just cut off the steam in cylinder No. 3, and that the piston in No. 1 has just arrived at the top of its stroke. At the same time the annular groove 20 in No. 3, moving downward, as indicated by the arrow, is just uncovering the steam-port to admit steam to the cylinder No. 1, while the piston of No. 1 is allowing full exhaust from cylinder No. 2. Shortly the piston of No. 1 25 in moving downward would close the exhaust. The corner not being cut away, this would occur when the piston of No. 2 had completed three-fourths of its upward or return stroke, when compression would commence. It is 30 here that the greater value of cutting away the piston-edge, before referred to, comes into play. By cutting away the portion Y (shown on the drawings, Fig. 3) the compression is reduced from one-fourth of the stroke to about one-eighth. This will be better understood 35 by examining the diagram of the valve-motion shown by Fig. 7. The engine takes steam at *a*, the commencement of the stroke, and the cut-off takes place at *b*, three-fourths of the 40 downstroke. Without this cut-away the exhaust would begin precisely at the end of the stroke, but by virtue of the part removed (represented by the distance Y) the exhaust takes place this much earlier at *c*, giving about the 45 usual amount of exhaust lead recommended in fast-running engines. Similarly the point where compression sets in is shifted by the same cause, and delayed until the crank travels the distance Y past the three-quarter part 50 of the stroke, and the compression begins at *d* seven-eighths of the upstroke. This description of the valve motion will serve for all the cylinders.

It will be noticed that the port-passages proper 55 belonging to the three cylinders are uniformly alike and occupy the same relative position on the central line running through the cylinders in the direction of the axial line of the shaft, giving to the steam remaining in the 60 passages belonging to cylinders 2 and 3, after the exhaust is closed, a degree of compression equal to about the pressure of the steam contained in the receiver R, in which case the effect of their clearance-space is rendered practically 65 *nil*. The passage leading to the high-pressure cylinder is an addition, and the waste of

steam it would cause at each stroke would be of a ruinous character in an ordinary engine. Here no such loss occurs, for the contained steam is not exhausted and wasted at every 70 stroke, as would be the case were this an ordinary engine, but is exhausted into an intermediate receiver, R, from which the cylinders 2 and 3 take their supply of steam. The quantity of this steam being the amount discharged from the first cylinder, the capacity of the receiver should be about equal to the combined contents of the two low-pressure cylinders. This intermediate receiver is a reservoir into which the steam exhausted from 75 the first cylinder is stored in readiness to be admitted to cylinders 2 and 3 when they are prepared to take it.

Instead of having two low-pressure cylinders of the same size, it is obvious that one 80 may be employed of that size—viz., double the area of the first cylinder—discharging into a second receiver, or, what is the same thing, a divided receiver, as shown in Fig. 9, and another lower-pressure cylinder of double the 85 capacity of the second cylinder may be used, which last cylinder shall alone exhaust into the atmosphere or condenser; but I prefer for the general purposes for which this invention is intended—to wit, the building of economical high-speed engines—to compound the cylinders as described. They are cheaper to fit up, and give an expansion of the steam of about five times, which will easily give double the power with the same steam of any common 90 non-compound engine, reaching up to the highest attainment of the automatic engine, without any of its complication.

A section of the intermediate receiver through the line *xx* of Fig. 5 is shown by Fig. 4. It will be seen by reference to these figures that the steam exhausted from the high-pressure cylinder entering the receiver by the port marked E' circulates freely all through the receiver, and that the cylinders 2 and 3 take 100 their steam therefrom through the ports marked S² and S³ and exhaust E² E³. From the bottom of the receiver a drain-pipe, I, leads, on which is fitted a steam-trap to automatically carry off the water of such condensation as may take place in the receiver. One other point to be noticed is the manner in which the revolving cranks and reciprocating pistons and rods are balanced. In the case of the cranks, as the center of gravity of the 110 triangle composing the cheeks of the same is precisely at the center of motion, the cranks are truly balanced, with the exception of the pins. The individual weight of each pin, together with the connecting-rod and attached 115 piston, are counterbalanced by a proper weight situated in the rim of the fly-wheel, as shown in Fig. 8, the rim being cast partly hollow, leaving the balance-weights W, W², and W³ cast solidly in. The weight W multiplied 120 by the leverage is made to equal one-half of the weight of the corresponding piston-rod and

crank-pin it is intended to balance. There being two fly-wheels, the full balance is effected between them.

As a finish to the engine, the cylinders are enveloped by a casing, *k*, of Russia iron, after being padded with non-conducting material, and this casing is secured in place by a polished iron cover, *L*, simply forced down as a lid from above, the head being previously padded. The whole exterior of the engine then presents a perfectly smooth and rounded contour.

I am aware of German Patents Nos. 6,948 and 8,577, and also of the United States Patent of Bown, No. 310,369, and I claim nothing disclosed in said patents.

What I claim as my invention, and desire to secure by Letters Patent, is—

1. In a multiple-cylinder compound engine, as described, the combination of the two low-pressure cylinders 2 and 3 with the high-pressure cylinder 1, all fitted with trunk-pistons, each having a circumferential groove playing over steam and exhaust ports and controlling the operation of the piston attached to the next following crank, substantially in the manner and for the purpose herein set forth.

2. In a multiple cylinder compound engine, as described, the combination of the circumferentially-grooved trunk-pistons with the steam and exhaust ports, the groove alternately matching the steam-inlet, and the steam-port leading to another cylinder in its downstroke, and the exhaust-port leading from that cylinder and the exhaust outlet-port on its upstroke, arranged substantially as specified and shown.

3. In a multiple-cylinder compound engine, as described, the combination of the high-pressure cylinder, the steam-passage *P*, and the groove in the piston 3, matching on its upstroke the exhaust-aperture *E'*, cut through

the wall of cylinder No. 3 directly into the intermediate receiver, *R*, arranged substantially in the manner and for the purpose specified and shown.

4. In combination with the pistons and connecting-rods of a multiple-cylinder engine, the shaft *B*, having balanced triangular crank-cheeks, the center of gravity coinciding with the center of motion, substantially as represented.

5. The combination of the inclosed crank-case *A* with the slotted cover-plates *H*, attached to the lower ends of the trunk-pistons, substantially in the manner and for the purpose specified.

6. The combination of the inclosed crank-case *A* with the interposed non-conducting shield *M*, arranged substantially in the manner and for the purpose described.

7. As an improvement in an engine, the combination of the inclosed crank-case *A* with the hollow heads *C C'*, formed with cavities in the body of the hub, and sleeve-journal bearings and oil-hole *Z*, leading from the interior of the case to the annular cavity in the hub, arranged substantially in the manner and for the purpose set forth.

8. As an improvement in an engine, the combination of the hollow trunk-piston, the cap perforated at *O*, the recessed follower *F*, and ball-jointed connecting-rod *D*, arranged substantially in the manner and for the purpose herein described.

9. The combination of the cylinders, their ports and grooved pistons, with a double or divided receiver, substantially as set forth.

In testimony whereof I have hereunto set my hand.

WILLIAM M. HENDERSON.
